DECOY

Frank H. Anderson, Des Moines, Iowa

Application March 11, 1957, Serial No. 45,183

Term of patent 3½ years

(Cl. D31—4)

Fig. 1 is a perspective view of a decoy showing my new design;

Fig. 2 is a side elevation thereof in the approximate attitude of the decoy when resting on the ground;

Fig. 3 is a plan view of my decoy; and

Figs. 4 and 5 are front and rear elevational views thereof respectively showing a rod projecting downwardly from the decoy being broken off for convenience of illustration.

I claim the ornamental design for a decoy, substantially as shown and described.
